UNITED STATES PATENT OFFICE

BYRON C. BOOTH, OF MUSKEGON HEIGHTS, MICHIGAN, ASSIGNOR TO THE BRUNSWICK-BALKE-COLLENDER COMPANY, OF CHICAGO, ILLINOIS, A CORPORATION OF DELAWARE

TOILET SEAT

Application filed November 2, 1927. Serial No. 230,537.

My invention relates to toilet seats, and more particularly to the type known as "open front and rear" seats.

"Open front and rear" seats are well known for their unusually high sanitary qualities, but the difficulty has always been in making them sufficiently strong to withstand the rigorous conditions of rough usage. Because of the narrowness of the side pieces they have but small surface contact with the hinge plates to which they are secured, and consequently, there is a tendency to tear loose from these plates.

One object of my invention is to obviate this difficulty by providing a seat of the type described which will be especially strong and durable.

A further object of my invention is to provide a member having the shape of an open front and rear toilet seat and composed of a plastic composition, and having a hinge element imbedded therein and covered thereby.

A still further object is to provide such a seat in which the insert and hinge lugs are one integral member.

Still a further object is to provide a method for the production of a seat having the characteristics described.

Other objects and advantages will become apparent as the description proceeds.

Referring to the drawings forming a part of this specification,

Fig. 1 is a plan view, partly in section, of a seat embodying my invention,

Fig. 2 is a sectional view taken on line 2—2 of Fig. 1;

Fig. 3 is a perspective view of the same, partly broken away, and

Fig. 4 shows a horizontal sectional view of a modified form of my invention.

The toilet seat of Figs. 1, 2 and 3 comprises two wing-shaped cores 1 of laminated wood. A pair of inserts 2 are provided and one is embedded in each of the cores. A hinge element 3 is integral with the inserts and the hinge element and inserts may be a malleable iron casting or may be made of other suitable material.

The inserts have corrugations 4 thereon for

gripping the cores and are perforated to receive pins 5.

The hinge element has shoulders 6 thereon which engage the ends of the cores.

A coating 7 of plastic material such as hard rubber, a phenolic condensation product, nitrocellulose etc. covers the cores and extends over the hinge elements, presenting a continuous and unbroken surface, particularly along the lines of juncture of the cores and hinge element.

The hinge element has openings 8 therein through which a pintle 9 extends, supported by standards 10.

The cores need not be laminated but may be in one piece and in fact may be made of different substances heretofore used in the art such as ground cork, wood shavings incorporated in a binder, or a cheaper grade of rubber. Or the core may be omitted and the wing portions may be made merely of a plastic material such as the coating 7 is composed of, and the inserts may be imbedded directly therein.

In the embodiment shown in Fig. 4, the core 21 is hollowed out in the rear so as to form a cavity 22, having side walls 23. This operation may conveniently be accomplished by a chain mortising machine. An insert 24 having exactly the shape of the cavity is then driven into it, the insert being integrally cast with the hinge element 25, as described above for the other embodiment. A coating of hard rubber 26 is molded over the cores and hinge element.

This embodiment forms a very rigid union between the inserts and cores, due to the fact that the former are surrounded on all sides by the material of the cores, excepting at the rear, while the necessity for pins to insure such a union and prevent angling of the core with respect to the hinge element is eliminated.

Fig. 4 also shows a modification of the hinge, in which a screw pintle 27 extends through the eye 28 and the supporting standard 29 and is threaded into a tubular portion 25 of the hinge element. This arrangement simplifies the construction somewhat by eliminating the long pintle and nuts shown in Fig.

1 and, since the pintles are screwed flush with the eye, the arrangement is especially neat and sanitary.

The coating which it will be observed is of substantial thickness possesses considerable inherent strength and assists the described metallic inserts in obtaining a secure joint between the hinge elements and the cores notwithstanding the narrowness of the sides of the seat. This combined action of the coating and inserts prevents the hinge element from tearing loose and the coating by projecting outwardly from the cores over the connection and hinge element effectively seals the cores and thereby prevents moisture from attacking the cores, thus adding greatly to the naturally high sanitary qualities of the open front and rear seat.

Obviously the inventive idea set forth in the claims may be embodied in constructions considerably different from that illustrated in the drawings and described in detail, and the specific devices illustrated may be modified in many particulars without departing from the invention.

By the designation "open front and rear type" as used in the specification and claims, is meant a seat in which the sides or wings are spaced apart at both the front and rear of the seat, the connection between the wings at the rear of the seat having no seating body supporting function and being spaced rearwardly from the seat proper or body supporting area, whereby within said area there is a rearwardly disposed space between the wings as well as a frontal space.

What I claim and desire to protect by Letters Patent is:

1. A toilet seat comprising seat wings having cores, a metallic insert for each of said cores imbedded in said cores and having an irregular surface for preventing withdrawal of said inserts, a hinge element integral with said inserts and a coating of a plastic composition covering said cores and said hinge element and having an uninterrupted surface at the points of juncture of said inserts and said hinge element.

2. A toilet seat comprising a pair of wooden cores having the shape of a wing, a metallic insert for each of said cores, imbedded therein, a hinge element integral with said cores and having an opening therein, and a coating of hard rubber on said cores and extending over said hinge element, a pintle extending through said opening and a pair of standards supporting said pintle.

3. A process for making a two piece toilet seat comprising the steps of joining two cores by driving into their rear ends inserts integral with a hinge element and then molding a plastic coating over said cores and said hinge element.

4. An open front and rear toilet seat comprising cores, a hinge element secured to said

cores at the rear thereof and a coating of plastic material extending over said cores and said element and having an uninterrupted surface at the points of juncture of said cores and said element.

5. A toilet seat comprising a pair of wing-shaped cores, a metallic insert embedded in each of said cores, shoulders engaging the ends of said cores, and a hinge element, said shoulders and hinge elements being integral with said insert.

6. A toilet seat comprising a pair of wing-shaped cores, a metallic insert embedded in each of said cores, shoulders engaging the ends of said cores, and a hinge element, said shoulders and hinge elements being integral with said insert, and a continuous coating of plastic material covering said cores, shoulders, and hinge element.

7. A toilet seat of the open front and rear type comprising a pair of wings, a hinge element constituting a connection between said wings at their rear ends and carrying parts projecting into the wings, a plastic composition surfacing extending completely over said wings and element thereby exteriorly uniting the wings and element into a unitary structure, and a support having a pivotal connection with said element, said support and said element constituting a hinge for said seat.

8. A toilet seat comprising a pair of members each composed of a plastic composition and each having the shape of a wing of a toilet seat of the open front and rear type, said members being spaced apart at their front and rear ends and having projecting portions of said plastic composition and a metallic hinge part element embedded in and coated by said projecting portions and uniting said members.

9. A toilet seat comprising a pair of members composed of a plastic composition and having the shape of the two wings of a toilet seat of the open front and rear type, said members having projecting portions of said plastic composition and a metallic element carrying a hinge part for said seat uniting said wings and embedded within and coated by said projecting portions which unite said metallic member and wings exteriorly into an integral structure.

10. A toilet seat comprising a pair of cores each forming a separate wing of a toilet seat of the open front and rear type, an element extending between said cores and joined thereto, and a coating of plastic composition enveloping said cores and uninterruptedly extending outwardly therefrom over said element.

11. A toilet seat comprising a pair of cores each forming a separate wing of a toilet seat of the open front and rear type, an element extending between said cores and joined thereto, and a coating of plastic composition

enveloping said cores and uninterruptedly extending therefrom over said element, and a hinge part carried by said element.

12. A toilet seat comprising a pair of wooden cores each forming a separate wing of a toilet seat of the open front and rear type, and inserts in each of said cores having rigid therewith an element extending between said cores and joining the same, a plastic composition coating enveloping said cores and uninterruptedly extending outwardly therefrom over said element, and a hinge part carried by said element.

13. A toilet seat comprising a pair of wooden cores each forming a separate wing of a toilet seat of the open front and rear type, and inserts in each of said cores having rigid and integral therewith an element extending between said cores and joining the same, a plastic composition coating enveloping said cores and uninterruptedly extending outwardly therefrom over said element, and a hinge part carried by said element.

14. A toilet seat comprising a pair of wooden cores each forming a separate wing of a toilet seat of the open front and rear type, and inserts in each of said cores having rigid therewith an element extending between said cores and joining the same, means for securing said inserts to said cores, a plastic composition coating enveloping said cores and uninterruptedly extending outwardly therefrom over said element, and a hinge part carried by said element.

15. A toilet seat comprising a pair of wooden cores each forming a separate wing of a toilet seat of the open front and rear type, and inserts in each of said cores having rigid and integral therewith, an element extending between said cores and joining the same, said inserts having roughened surfaces to resist withdrawal from said cores, a plastic composition coating enveloping said cores and uninterruptedly extending outwardly therefrom over said element, and a hinge part carried by said element.

16. An open front and rear toilet seat comprising a pair of members each composed of a plastic composition and each having the shape of a wing of a toilet seat with open spaces within the seat or body supporting area at the front and rear ends of said members, said members being spaced apart to provide said areas and eliminate seat portions therebetween at their front and rear ends, the plastic composition extending between said members at their rear ends and forming a connection between the same, hinging means carried by said connection and a support engaging said hinging means and supporting the same for pivotal movement, said connection being spaced rearwardly of the open seat area at the rear end of said seat so as not to destroy the open rear character of said seat.

17. An open front and rear toilet seat com-

prising a pair of members each composed of a plastic composition and each having the shape of a wing of a toilet seat with open spaces within the seat or body supporting area at the front and rear ends of said members, said members being spaced apart to provide said areas and eliminate seat portions therebetween at their front and rear ends, a connecting element joining the rear ends of said members the plastic composition extending between said members at their rear ends over said element and assisting the latter in forming a connection between the same, hinging means carried by said connection and a support engaging said hinging means and supporting the same for pivotal movement, said connection being spaced rearwardly of the open seat area at the rear end of said seat so as not to destroy the open rear character of said seat.
